United States Patent Office

Des. 191,731
Patented Nov. 7, 1961

191,731

OVEN

Hilbert W. Pieplow, Milwaukee, Wis., assignor, by mesne assignments, to Basic Products Corporation, Milwaukee, Wis., a corporation of Wisconsin

Filed Sept. 22, 1958, Ser. No. 52,725

Term of patent 14 years

(Cl. D81—10)

FIG. 1

FIG.2

FIG. 1 is a perspective view of an oven looking from the righthand corner;

FIG. 2 is a perspective view looking from the lefthand corner.

The rear surface of the oven is substantially plain.

My design for the oven disclosed is characterized by the hinge and latch unit having the configurations shown.

I claim:

The ornamental design for an oven, substantially as shown and described.
